UNITED STATES PATENT OFFICE.

ALBERT B. DICK AND ERNEST BRASSEUR, OF CHICAGO, ILLINOIS,
ASSIGNORS TO A. B. DICK COMPANY, OF CHICAGO, ILLINOIS,
A CORPORATION OF ILLINOIS.

PAPER-FEEDING APPARATUS.

SPECIFICATION forming part of Letters Patent No. 749,985, dated January 19, 1904.

Application filed August 1, 1903. Serial No. 167,932. (No model.)

To all whom it may concern:

Be it known that we, ALBERT B. DICK, a citizen of the United States, and ERNEST BRASSEUR, a subject of the King of Belgium, both residing at Chicago, in the county of Cook and State of Illinois, have invented a certain new and useful Improvement in Paper-Feeding Apparatus, of which the following is a specification.

10 The object of the invention is to provide an automatic paper-feeding apparatus which shall consist of few parts, compact and durable in form, efficient in use, and one in which the feeding of more than one sheet at a time shall be precluded.

15 A further object is to provide apparatus of this description which shall be relatively cheap of manufacture, which may be readily adjusted in use, and which shall afford ready 20 provision for repair and renewal of interchangeable parts.

25 In carrying out the invention in an approved form we employ a series of rolls in juxtaposition to which may be placed a paper-tray upon which the sheets to be fed may be arranged and a bed or other device upon which the sheets fed by the rolls may be passed to the printing or other machine in which they are to be subsequently treated. Preferably 30 these rolls are actuated from a common point, and, if desired, power may be transmitted from the mechanism in connection with which the feeding apparatus is employed. The feeding-rolls may be given either an intermittent 35 or continuous motion in the direction of the printing or other apparatus, but combined with one or more of such rolls we employ a paper-stopping device, such as another roll or rolls, to which motion, also either intermittent 40 or continuous, may be imparted, but in a contrary direction or a direction opposite to the printing or other apparatus. Between this roll (hereinafter referred to as the "reverse-roll") and one of the feed-rolls the paper to 45 be fed is passed, the pile being in juxtaposition thereto, but only one sheet thereof (in the present instance the lowermost sheet) be-

ing permitted to pass between the reverse-roll and the feed-roll coacting therewith.

In a preferred form in which the invention 50 may be embodied, but to which such invention is not limited, we employ a system of three rolls operatively connected with the source of power above mentioned, the connections being so arranged as that there will 55 be imparted to two of these feed-rolls an intermittent movement in the direction of the printing mechanism and to the third a continuous movement in the same direction. Coacting with one of these intermittently-operating 60 feed-rolls is the continuously-rotating reverse-roll, between which and said feed-roll the paper to be fed is designed to pass. Said feed-roll and said reverse-roll are preferably adjustable relatively to each other in 65 order to provide for variation in the thickness of the sheets to be fed between the same.

In the drawings we have illustrated a form in which the invention may be advantageously applied to a stencil-printing apparatus, the 70 feeding mechanism above referred to being adapted to pass the sheets of impression-paper therefrom and to the printing mechanism.

In the drawings, Figure 1 is an end view; Fig. 2, a side elevation looking from the left 75 of Fig. 1; Fig. 3, a vertical section on the line 3 3, Fig. 1; and Fig. 4 a similar section on the line 4 4 of Fig. 1.

Referring to the drawings, in which similar letters denote corresponding parts, A A' designate the side members of the frame, here shown as mounted upon a suitable base A'. Said frame and base may, if desired, be common to the paper-feeding apparatus and the printing or other mechanism with which such 85 paper-feeding apparatus is combined. In the side member A of the frame is journaled the shaft a , upon which are mounted the sprocket-wheel a' , the continuously-toothed gear a^2 , the large stop-wheel a^3 , and the mutilated gear a^4 , 90 all having continuous rotary movement with the sprocket-wheel a' . Coacting with the continuous gear a^2 is a smaller gear c , mounted upon and rotating with the shaft c' , carrying

the roll C, to which is thereby imparted a continuous movement in the direction of the printing mechanism. Also mounted upon and secured to the shaft e' , but within the side member A of the frame, is a gear c^2 . Upon this shaft may also be mounted, if desired, a pulley coacting with a belt for the purpose of transmitting movement to suitable rolls or other devices designed to act upon the sheets 10 after they have been fed in the manner herein described. Such rolls or other devices not being part of the present invention will not be herein described in detail.

e designates the shaft of the feed-roll E. 15 The ends of this shaft are journaled in the side members A A' of the frame, that end adjacent to the side member A extending through the same and being provided outside said side member with a gear e' and a stop-wheel e^2 , 20 both of which are keyed or otherwise secured to said shaft e . As clearly shown in Fig. 1, the gear e' lies directly under and in co-operative relation to the mutilated gear a^4 , while the small stop-wheel e^2 lies directly under and 25 in co-operative relation to the large stop-wheel a^3 . The small stop-wheel e^2 is provided with an ear e^3 , having a concave surface corresponding to the curvature of the periphery of the large stop-wheel a^3 . This concave surface 30 rides against the periphery of the latter during the major portion of the revolution of said large stop-wheel a^3 . The latter is provided, however, with notches or recesses a^5 a^6 , each forming shoulders on the periphery of said 35 wheel. When during the revolution of said large stop-wheel a^3 the notch a^6 reaches the ear e^3 , the edge of the latter enters said notch, so that the small stop-wheel e^2 is caused to rotate with said wheel a^3 until said ear is again 40 brought into juxtaposition with the periphery of the latter at the notch a^5 , whereupon the concave periphery of the ear e^3 of the small stop-wheel e^2 again slides in contact with the periphery of the large stop-wheel a^3 . The 45 teeth of the mutilated gear a^4 cover a portion of the periphery of that wheel corresponding to the distance between the notches a^5 a^6 . These teeth therefore are brought into operative relation to the teeth of the gear e' the movement the notch a^6 on the large stop-wheel a^3 50 and the ear e^3 of the small stop-wheel e^2 come into engagement, with the result that by means of said mutilated gear the feed-roll shaft e , upon which both the gear e' and small stop-wheel e^2 are mounted, will be rotated.

E' designates a clutch on the shaft e , whereby after said shaft e has been brought to a stop the roll E may still be revolved thereon by the pull of the paper fed over said roll, as 60 will presently be described.

F designates a bar, the ends whereof are mounted in the upwardly-extending portions f of the side frames A A'. Secured to or formed integral with this bar are the dependent arms f' f^2 .

G designates the reverse-roll shaft, one end whereof is mounted in the end of the arm f^2 , depending from the bar F. The other end of said shaft passes through a U-shaped recess in the end of the arm f' , and keyed or otherwise secured to it at this end is a gear g , meshing with a larger gear H, loosely carried by the shaft e of the intermittent feed-roll E and which in turn is driven by the gear c^2 on the shaft of the constantly-moving roll C. Regardless, therefore, of whether the shaft of the intermittent roll E be moving or still there is a constant movement of the gear H, mounted on that shaft, and therefore of the gear g of the reverse-roll shaft G.

80 The paper-stopping device is here shown as comprising the reverse-rolls I. Instead of employing a reverse-roll continuous from end to end like the feed-roll E we prefer to employ two or more separated reverse-rolls, and 85 these are here shown as mounted upon the shaft G within the housings i, adjustably carried by the bar F. The forward edges of these housings serve to level the advancing edge of the pile. Preferably the reverse-roll shaft G 90 will, as shown in Figs. 3 and 4, lie not directly above the feed-roll shaft e , but slightly forward of the same—i. e., toward the paper pile—whereby greater efficiency of the reverse-rolls is obtained in their coaction with 95 the sheets above the lowermost sheet of the pile. The bar F is therefore suitably adjustable in a horizontal plane, as are also the reverse-rolls I and the hangers J, in which with the arms f' f^2 the reverse-roll shaft G is 100 mounted.

l designates the shaft of an auxiliary intermittent feed-roll or separator-roll L. This shaft is journaled in the side members A A', one end extending through the side member 105 A and being provided outside the same with the gear l' , meshing with an idler-gear l^2 , which in turn meshes with and is driven by the gear e' , carried by the shaft e of the intermittent feed-roll E. It will therefore be seen 110 that both the intermittent feed-roll E and the auxiliary intermittent feed-roll L move and are still together. Like the intermittent feed-roll E and its shaft, the auxiliary feed-roll L and its shaft are provided with a clutch, so 115 that when the shaft has been brought to a stop the roll may still be rotated upon such shaft under the pull of the paper passing over the same.

In practice we prefer that the peripheries 120 of the rolls C, E, and L shall be of rubber or other suitable substance and that in addition the periphery of one of these rolls—as, for instance, the roll L—shall be longitudinally fluted, as illustrated in Fig. 4.

M M designate gravity-rolls, preferably of metal and provided with milled peripheries. These are mounted upon a shaft m , the ends whereof are journaled in hangers pivoted at m' to the downwardly-projecting arms f' f^2 of the 125

bar F. These gravity-rolls are arranged directly above the feed-roll C, their purpose being to hold the sheets in contact with the last-named roll.

5 In practice a suitable paper-tray (not shown) will be employed, its end terminating near the intermittent feed-roll L. Upon such tray and upon said roll L the pile of paper is placed and pressed forward against and below the forward-curved corners of the housings i of the reverse-rolls I. Power being applied—as, for instance, by means of the sprocket-wheel or other suitable connection—the feed-roll C is set in continuous operation and the feed-rolls 10 E and L in intermittent operation, the latter being due to the coaction of the stop-wheels a^3 and e^2 . At each movement of the feed-rolls L and E the lowermost sheet of the pile is fed forward over the feed-roll L and between the feed-roll E and reverse-rolls I to a point where it is seized and passed farther forward by the continuously-operating feed-roll C and the gravity-rolls M. The adjustment of the intermittent feed-roll E and the reverse-rolls I 15 relatively to each other is such as to permit but a single sheet to pass between the same. Said reverse-rolls therefore operating in a direction contrary to that of the intermittent feed-roll E act upon the sheets above the lowermost sheet, pressing them backward, so as to preclude their being carried through the feeding apparatus—i. e., between the intermittent feed-roll E and said reverse-rolls. Should the sheets be of such length as that each intermittent movement of the feed-rolls E and L will not entirely pass the lowermost sheet beyond the point of coaction between said feed-roll E and the reverse-rolls I, the continuous movement of the roll C will nevertheless draw 20 such sheet along through the feeding apparatus, the clutches on the shafts of the intermittent rolls E and L permitting these rolls to be operated after the shafts have become still by the pull of the sheet.

45 Having now described our invention, what we claim as new, and desire to secure by Letters Patent, is as follows:

1. In paper-feeding apparatus, the combination with a bed adapted to support a pile of 50 sheets in a fixed plane and a feed-roll mounted below said pile and coacting successively with the lowermost sheets thereof, of a paper-stopping device in operative relation to said feed-roll and between which device and roll the paper to be fed is passed, and means for imparting movement concurrently to said device and said feed-roll, substantially as set forth.

2. In paper-feeding apparatus, the combination with a bed adapted to support a pile of sheets and a feed-roll mounted below said pile 60 and coacting successively with the lowermost sheets thereof, of a rotary paper-stopping device in operative relation to said feed-roll and between which device and roll the paper to be fed is passed, and means for imparting movement to said device, substantially as set forth.

3. In paper-feeding apparatus, the combination with a bed adapted to support a pile of sheets and a feed-roll mounted below said pile 65 and coacting successively with the lowermost sheets thereof, of an adjustable rotary paper-stopping device in operative relation to said feed-roll and between which device and roll the paper to be fed is passed, and means for imparting movement to said device, substantially as set forth.

4. In paper-feeding apparatus, the combination with means for supporting a pile of sheets in an approximately horizontal plane and a feed-roll mounted below such pile and coacting 80 successively with the lowermost sheet thereof, of a reverse-roll in co-operative relation to said feed-roll, and means for operating said feed-roll in one direction and said reverse-roll in the opposite direction, substantially as set forth.

5. In paper-feeding apparatus, the combination with means for supporting a pile of sheets in an approximately horizontal plane and a feed-roll mounted below such pile and coacting 90 successively with the lowermost sheet thereof, of means for feeding such lowermost sheet to said feed-roll, a reverse-roll in co-operative relation to said feed-roll, and mechanism for operating said feed-roll in one direction and said 95 reverse-roll in the opposite direction, substantially as set forth.

6. In paper-feeding apparatus, the combination with means for supporting a pile of sheets in an approximately horizontal plane, of a 100 feed-roll and a separator-roll mounted below such pile and coacting successively with the lowermost sheet thereof, a reverse-roll in co-operative relation to said feed-roll, and means for operating said feed and separator rolls in 105 one direction and said reverse-roll in the opposite direction, substantially as set forth.

This specification signed and witnessed this 26th day of June, 1903.

ALBERT B. DICK.
ERNEST BRASSEUR.
